UNITED STATES PATENT OFFICE

ARTHUR E. PETERS, OF PHILLIPSBURG, NEW JERSEY, ASSIGNOR TO INGERSOLL-RAND COMPANY, OF JERSEY CITY, NEW JERSEY, A CORPORATION OF NEW JERSEY

DRILL SHARPENER

Application filed April 1, 1930. Serial No. 440,719.

This invention relates to drill sharpeners, but more particularly to that type of sharpener in which the work is clamped or forged between relatively movable elements, such as an anvil block and a cross head, both of which may be provided with die members of suitable form for either clamping the work securely in position or for forging operations, such as forming the shanks and bits of drill steels and similar working implements.

One object of the invention is to prevent destructive impact of the cross head against the anvil block by suitable cushioning devices adapted to become operative as the cross head nears the end of its clamping or forging stroke.

Other objects will be in part obvious and in part pointed out hereinafter.

In the accompanying drawings illustrating the invention and in which similar reference characters refer to similar parts,

Figure 1 is a sectional elevation of a drill sharpener constructed in accordance with the practice of the invention, and

Figure 2 is a transverse view taken through Figure 1 on the line 2—2 looking in the direction indicated by the arrows.

Referring more particularly to the drawings, A represents generally a drill sharpener comprising a base B upon which is disposed a clamping cylinder C shown for the purpose of illustration as forming an integral part of an anvil block D.

The anvil block D is provided with a bore E to receive slidably a post or column F to the upper end of which is secured a cross head G.

In the opposing faces of the anvil block D and the cross head G are disposed die members which are designated according to

pairs as H and J. These die members are merely shown for illustrative purposes and it is to be understood that any dies suitable for the respective work for which they may be intended may be substituted for those shown.

The lower portion of the base B may be in the form of a pressure fluid supply reservoir K which may communicate with a source of pressure fluid supply (not shown) through a connection L threaded in the base B. In

the upper region of the base B is an end wall O which forms a head for the lower end of the clamping cylinder C and depending therefrom is a projection or wall P which may be of annular shape and has a bore Q for the reception of a stem R preferably formed integrally with a clamping piston S reciprocable in the clamping cylinder C.

The clamping piston S and the stem R are provided with a bore T to receive a reduced extension U of the rod F. By forming the reduced extension U on the rod F a shoulder V is provided on the rod to form an abutment for the upper end of the piston S.

The extension U is of such length that its lower end W projects beyond the corresponding end of the stem R, and the projecting end W is provided with threads X for the accommodation of a nut Y which bears against the free end of the stem R to press the clamping piston S firmly against the shoulder V.

The stem R and the reduced portion U of the rod F are, in effect, a raising piston, since their lowermost ends are constantly exposed to the pressure fluid in the supply reservoir K. The arrangement is such that in the absence of any opposing pressures the pressure fluid acting against the lower ends of the rod F and the stem R, as well as against the nut Y will raise the cross head G relatively to the anvil block and will, therefore, also raise the clamping piston S. Preferably the stem R is provided with suitable sealing means such as a series of rings Z which may be disposed in grooves b in the stem R in a well known manner to prevent leakage of pressure fluid from the supply reservoir K through the bore Q.

The means provided for controlling the movement of the clamping piston S may consist of a manually controlled valve c arranged in a valve chest d on the side of the sharpener, as for instance, adjacent the clamping cylinder C. A guide bushing e may be disposed within the valve chest d to form a renewable wearing surface for the valve c.

The valve c may comprise a pair of end heads f and g connected by a stem h, and to one end of the valve c, as for instance, the

free end of the head *f*, is connected a link *j* which may be connected to a suitable manipulating device, such as a crank *k* in any suitable manner and whereby the valve *c* may be manually actuated from one limiting position to the other.

The pressure fluid controlled by the valve *c* is conveyed to the valve chest by a passage *o* which leads from the supply reservoir *K* and opens into a port *p* in the valve chest *d* and the bushing *e*. The port *p* is so located that it may be controlled by the head *f* of the valve. The pressure fluid thus admitted to the valve chest may pass around the stem *h* and through an inlet passage *q* leading from the valve chest to the upper end of the clamping cylinder *C*.

In order to provide an escape for the pressure fluid utilized for actuating the clamping piston *S* downwardly, the valve chest is provided with a port *r* in the bushing *e* and located below the passage *q*. The port *r* opens into an exhaust passage *s* located in the clamping cylinder *C* and in the base *B* and which passage *s* opens into an exhaust chamber *t* encircling the wall *P*. A port *u* in the side of the base *B* affords communication between the exhaust chamber *t* and the atmosphere.

In drill sharpeners of the type to which the present invention pertains the reciprocable parts, such as the cross head *G*, the clamping piston *S* and the rod *F* are of necessity of rugged construction and therefore of considerable weight. During their operation it is essential that they reciprocate at a rapid rate for forging the working implements. It is therefore desirable that means be provided to avoid severe impact of the movable elements against the stationary elements since, otherwise, these parts may become seriously damaged or broken. The present invention contemplates the provision of means for preventing destructive impact of the cross head *G* against the anvil block or of the clamping piston *S* against the base *B* at the end of the downward stroke of these elements. To this end the stem *R* is provided with a recess *v* preferably in the form of an annular groove through which the air beneath the piston *S* may escape into the bore *Q* and thence to the exhaust chamber *t* through a port or ports *w* in the wall *P*.

The groove *v* is preferably of such extent that it will be constantly in communication with the ports *w*. At the upper end of the groove *v* and forming a part of the stem *R* is a shoulder *x* which is adapted to move into the bore *Q* as the piston *S* nears the end of its downward stroke to prevent the complete expulsion of the air from beneath the said piston *S*. Preferably the lower end of the piston *S* is provided with a cavity or recess *y* to form a cushioning or compression chamber to accommodate the compressed air en-

trapped beneath the piston *S* after the shoulder *x* has cut off communication between the clamping cylinder *C* and the ports *w*.

In order to prevent the drawing of a vacuum beneath the clamping piston *S* as the clamping piston is being raised, the wall *O* is provided with an opening *z* which may be threaded to receive a removable valve seat or cage 70 2 provided with ports 3 for admitting atmospheric air into the clamping cylinder *C*.

The upper end of the cage 2 is in the form of a valve seat 4 to accommodate a check valve 5 in the form of a plate and the check valve may be guided with respect to the seat 4 by means of a rod or bolt 6 slidable in a bore 7 in the valve cage 2. The valve plate 5 may be suitably clamped to the rod 6 by means of a nut 8, and on the lower end of the rod 6 is threaded a nut 9 which is adapted to abut the end of the valve cage 2 for limiting the degree of lift of the valve plate 5.

The following is a brief description of the operation of the device: Let it be assumed that the valve *c* occupies a position in which communication is cut off between the passages *o* and *q*. In this position of the valve *c* the upper end of the clamping cylinder *C* will be in communication with the atmosphere through the passage *q* and *s*, the exhaust chamber *t* and the port *u*. The pressure fluid acting against the raising piston, such as the end of the rod *F* and the nut *Y*, will then raise the piston *S* and the elements connected thereto to the position illustrated in Figure 1. If then it be desired to lower the cross head *G* for clamping an implement therebetween or for forging purposes the valve *c* may be raised to permit the flow of pressure fluid from the supply reservoir *K* through the passage *o* and the passage *q* into the upper end 100 105 of the clamping cylinder *C*. The clamping piston *S* together with the cross head *G* will then be actuated downwardly.

During a portion of the downward stroke of the clamping piston *S* some of the air in the lower end of the clamping cylinder *C* will be forced therefrom by the piston *S* through the annular groove *v* and the ports *w* into the exhaust chamber *t* from whence it will flow through the port *u* to the atmosphere. As 110 115 the piston *S* approaches the end of its downward stroke the shoulder *x* will enter the upper end of the bore *Q*, thus preventing the further flow of air from the clamping cylinder *C*. The air remaining in the clamping cylinder *C* will then be compressed and will exert a sufficient cushioning effect against the piston *S* to prevent actual impact of the piston *S* against the wall or head *O*. The cushioning force of the air thus compressed, however, will not be of sufficient value to materially retard the downward stroke of the cross head against the work. This is due to the facts that the shoulder *x* is so located as to assure only a sufficient amount of air beneath 120 125 130

the piston S to prevent contact between the said piston and the head O, and also to the volume of the recess y which, in effect, is a cushioning chamber.

5 Upon reversal of the valve c the passage q will again be associated with the passage s. The pressure fluid utilized for actuating the cross head G downwardly will then escape from the clamping cylinder C into the exhaust chamber t, thence to the atmosphere through the port u. Upon the exhausting of pressure fluid from the clamping cylinder the pressure fluid acting against the raising piston will then again raise the reciprocable parts, such as the clamping piston S and the cross head G. During this upward movement of these parts the valve plate 5 will be raised and air will flow into the cylinder C through the ports 3 to assure against the drawing of a vacuum beneath the piston S and therefore the retardation of the upward movement of the cross head.

In practice the present invention has been found to be unusually efficient as a means for preventing breakage of the reciprocatory parts of the sharpener. One desirable feature of the invention is that, due to the provision of the exhaust chamber t within the base B, the pressure fluid discharged from the clamping cylinder C, as well as air expelled from beneath the piston S, may be suitably controlled during its course from the clamping cylinder and may therefore be directed to the atmosphere at points where it will not cause the agitation of dust and other matter in the vicinity of the sharpener. This arrangement also obviates the undesirable occurrence of exposing the operator to currents of exhaust fluid issuing from the sharpener.

40 I claim:

1. In a drill sharpener, the combination of an anvil block and a cross head reciprocable with respect to the anvil block, a base having a bore to form a guide, a clamping cylinder, a clamping piston in the clamping cylinder connected to the cross head having a stem reciprocating in the bore, said base having relief ports to communicate the bore with the atmosphere, there being a recess in the stem affording communication between the clamping cylinder and the relief ports, pressure actuated means for raising the cross head and the piston, and means on the stem to cooperate with the bore for cutting off the flow of the compression to the relief ports during the clamping stroke of the piston, thereby entrapping air in the clamping cylinder to cushion the final clamping stroke of the piston.

60 2. In a drill sharpener, the combination of an anvil block and a cross head reciprocable with respect to the anvil block, a base having a bore to form a guide, a clamping cylinder, a piston in the clamping cylinder connected to actuate the cross head and having a stem re-

ciprocating in the bore, said base having relief ports to communicate the bore with the atmosphere, there being an annular groove in the stem to convey compression from the clamping cylinder to the ports during a portion of the clamping stroke of the piston, pressure actuated means for raising the piston and the cross head, means on the stem movable into the bore to cut off the flow of compression to the relief ports as the piston nears the end of its clamping stroke, thereby entrapping air in the clamping cylinder to cushion the final portion of the clamping stroke of the piston, and means for admitting air into the cylinder to prevent the drawing of a vacuum therein during the return stroke of the piston.

3. In a drill sharpener, the combination of an anvil block and a cross head reciprocable with respect to the anvil block, a base forming a raising cylinder, a clamping cylinder, a clamping piston in the clamping cylinder and connected to move the cross head toward the anvil block, a stem on the clamping piston forming a raising piston for raising the cross head, said raising cylinder having compression relief ports therein, there being a recess in the stem to convey compression from the clamping cylinder to the ports during the down stroke of the clamping piston, and means on the stem to cooperate with the raising cylinder for cutting off the flow of compression from the clamping cylinder during the down stroke of the clamping piston, thereby entrapping air in the clamping cylinder to cushion the subsequent downward movement of the clamping piston.

4. In a drill sharpener, the combination of an anvil block and a cross head reciprocable with respect to the anvil block, a base forming a raising cylinder and having an exhaust chamber therein, a clamping cylinder, a clamping piston in the clamping cylinder and connected to actuate the cross head toward the anvil block, a stem on the clamping piston reciprocable in the raising cylinder and forming a raising piston for raising the cross head, said raising cylinder having compression relief ports opening into the exhaust chamber, there being an annular groove in the stem to convey compression from the clamping cylinder to the ports during a portion of the down stroke of the pistons, and a shoulder on the stem movable into the raising cylinder for cutting off the flow of compression from the clamping cylinder to the ports as the clamping piston approaches the end of its downward stroke, thereby entrapping compression beneath the clamping piston to cushion the piston during the remaining portion of its downward stroke.

5. In a drill sharpener, the combination of an anvil block and a cross head reciprocable with respect to the anvil block, a base forming

a raising cylinder and having an exhaust chamber therein, a clamping cylinder, a clamping piston in the clamping cylinder and connected to actuate the cross head toward the anvil block, a stem on the clamping piston reciprocable in the raising cylinder and forming a raising piston for raising the cross head, said raising cylinder having compression relief ports opening into the exhaust chamber, there being an annular groove in the stem to convey compression from the clamping cylinder to the ports during a portion of the down stroke of the pistons, a shoulder on the stem movable into the raising cylinder for cutting off the flow of compression from the clamping cylinder to the ports as the clamping piston approaches the end of its downward stroke, thereby entrapping compression beneath the clamping piston to cushion the piston during the remaining portion of its downward stroke, a port in the base to admit air into the clamping cylinder beneath the clamping piston to prevent the drawing of a vacuum during the upward stroke of the piston, and a check valve to control the last mentioned port.

In testimony whereof I have signed this specification.

ARTHUR E. PETERS.
